CLAIM

The ornamental design for a support, as shown and described.

DESCRIPTION

FIG. 1 is a right, top, front perspective view of a support embodying our new design as shown in a retracted position with mounting bracket environment;

FIG. 2 is a front elevational view thereof;

FIG. 3 is a rear elevational view thereof;

FIG. 4 is a top plan view thereof;

FIG. 5 is a right side elevational view thereof, the left side elevational view thereof being a mirror image of the right side shown;

FIG. 6 is bottom plan view thereof;

FIG. 7 is a right, top, front perspective view of a support embodying our new design as shown in an extended position with mounting bracket environment;

FIG. 8 is a front elevational view thereof with the mounting bracket environment shown partially broken away;

FIG. 9 is a rear elevational view thereof;

FIG. 10 is a top plan view thereof;

FIG. 11 is a right side elevational view thereof, the left side elevational view thereof being a mirror image of the right side shown; and,

FIG. 12 is bottom plan view thereof.

The mounting bracket is shown as partially broken away to indicate that no particular length is claimed.

The support is shown as partially broken away to indicate that no particular length is claimed. The portions of the support shown in broken lines form no part of the claimed design.

In a preferred embodiment, the nature of this product is a support which is primarily useful for adjustably mounting electronic devices, such as various displays and monitors.
